MINERAL MINING AND LOADING MACHINE
HAVING A TRANSVERSE CONVEYOR ON A
VERTICALLY ADJUSTABLE MINING HEAD
Ronald Cameron, Cappielow, Greenock, Scotland, as
signor to Joy Manufacturing Company, Pittsburgh, Pa.,
a corporation of Pennsylvania
Filed Apr. 15, 1958, Ser. No. 728,700
8 Claims. (Cl. 262—9)

This invention has reference to mineral mining and loading machines and more particularly to machines of the kind provided with a mobile base and a mining head extending forwardly from one or both ends thereof, said head, or each head, embodying mineral cutting or disintegrating mechanism which, as the mobile base is advanced, cuts the roof, floor and side wall of the mineral face.

The present invention has for its object to provide a mineral mining and loading machine of the kind set forth with simplified means whereby the cut or disintegrated material is more quickly discharged from the machine to be loaded out, as for example, onto a conventional face conveyor. Another object is to provide an improved reversible mining and loading machine having a cutting and disintegrating head mechanism at each end of the mobile base, whereby need for turning the machine around at the end of each cut is eliminated. A further object is to provide an improved double ended reversible mining and loading machine, wherein the trailing head mechanism may be collapsed to facilitate machine movement. Yet another object is to provide an improved mining and loading machine having a tiltable cutting and disintegrating head mechanism mounted at the front end of the machine-base and carrying conveying means whereby the disintegrated mineral may be discharged laterally in advance of the base. A still further object is to provide an improved mining and loading machine of the reversible double ended type wherein both heads are tiltable and collapsible, and each carry conveying means. These and other objects and advantages of the invention will, however, hereinafter more fully appear.

According to the present invention a mineral mining and loading machine comprises a mobile base, a mining head extending forwardly from one or both ends of the mobile base, each head embodying cutting or disintegrating mechanism which removes the material from the mineral face to form a passageway in the mine vein, which passageway permits the machine to advance, means whereby the head, or each head, can be adjusted vertically relative to the mobile base, and a transversely extending conveyor carried by the head, or each head, which conveyor is such that it will receive and support the cut or disintegrated material discharged thereto from the cutting or disintegrating mechanism and convey such material so that it is discharged laterally of the machine path in advance of the mobile base.

The transversely extending conveyors may take many forms. Thus, for illustrative purposes, they may be in the form of endless chains with flights extending between the chains at spaced distances apart and a fixed deck over which the upper run of the flights pass to scrape the mineral deposited thereon and discharge said material laterally of the machine. Or said conveyors may be in the form of endless belt conveyors. Or the conveyors may be of the type known as apron conveyors. In all cases the said conveyors must be such that they will receive, support and convey the material laterally in advance of the mobile base.

In the accompanying drawings there is shown for purposes of illustration one form which the invention may assume in practice.

2

In the drawings:

FIG. 1 is a plan view of one construction of a mineral mining and loading machine in accordance with the invention;

FIG. 2 is a front elevation of FIG. 1 looking to the right;

FIG. 3 is a side elevation of FIG. 1; and

FIG. 4 is a section on a larger scale on the line 4—4 of FIG. 3.

10 The mining and loading machine is herein for illustrative purposes of the longwall type, and in the drawings 10 denotes a mobile base which is here shown mounted on crawler treads 11 by which the mining and loading machine can be advanced in either direction. Projecting 15 longitudinally forwardly from each end of the base is a frame 12 pivotally supported by the base as at 13 whereby by tilting movements it can be raised and lowered relative to the base in a vertical plane.

Each frame carries a mining head in the form of mineral cutting or disintegrating mechanism. Such mechanisms may assume various forms, and in the embodiment of the invention shown each such mechanism comprises rotary cutters 14 mounted on horizontal parallel shafts 15 extending longitudinally of the mobile base and driven by any suitable power unit carried by the mobile base, and also endless loop cutter chains 16 arranged to travel in suitable guides 17 and to cut the plane roof, floor and side wall of the mineral face. The rotary cutters and the chain cutters are raised and lowered relative to the base by 20 tilting of their respective frames. Located immediately to the rear of the rotary and chain cutters and supported by each frame is a transverse conveyor 18 which may be of any suitable form. In the embodiment of the invention shown each conveyor comprises a fixed transversely extending deck 19, endless chains 20 positioned at each 25 side of the deck and a series of flights 21 extending between the chains, the upper run of flights being arranged to bear on and to travel over said deck. Each conveyor is driven by a tubular driving shaft 22 on which are fastened sprocket wheels 23 over which are passed the chains 20. Each conveyor is slightly inclined upwardly 30 towards one end thereof and the deck is provided with a correspondingly inclined extension 24. This end of the conveyor constitutes the discharge end.

45 When mining mineral such as coal the machine can be advanced in either direction along the longwall face, the leading rotary cutters and chain cutters continuously cutting and breaking, as the machine advances, the floor, roof and side wall of the coal face and the coal bounded thereby. The cut or disintegrated coal or other mineral immediately passes or falls onto the deck 19 from which it is pushed by the upper run of flights to be discharged at the side of the conveyor in advance of the mobile base. The disintegrated coal is discharged onto a conventional 50 face conveyor laid parallel with the face outside of the machine path along the face. Evidently the mineral may be discharged onto other forms of conveying means, in a well-known manner.

55 As a result of this invention an improved mining and loading machine is provided having a mobile base carrying an adjustable cutting and disintegrating head which in turn carries conveying means whereby the mineral dislodged and disintegrated by the head may be conveyed laterally out of the machine path. By mounting the conveyor on the tiltable head in advance of the base, the disintegrated mineral may be discharged laterally in advance of the base. The provision of a tiltable cutting and disintegrating head at each end of the base eliminates the need for turning the machine around at the end of each cut. By collapsing the trailing head, compactness is obtained and, during traveling about the mine, operation is made more easy with both heads collapsed. These and

other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A mineral mining and loading machine comprising a mobile base, a mining head pivotally secured to said mobile base adjacent one end thereof to be vertically movable with respect thereto, said mining head extending outwardly beyond said one end of said mobile base, said head having a cutting or disintegrating means for removing material from the mineral face to provide a passageway in the material being mined to permit the machine to advance, means for adjusting said head vertically relative to said mobile base, a conveyor carried by said head and positioned on said head immediately to the rear of said cutting means for receiving the disintegrated material, and said conveyor extending transversely of said mobile base to convey such material to one side of said machine in advance of said mobile base.

2. A mineral mining and loading machine comprising a mobile base, a mining head pivotally secured to said mobile base adjacent one end thereof to be vertically movable with respect thereto, said mining head extending outwardly beyond said one end of said mobile base, said head having a cutting or disintegrating means for removing material from the mineral face to provide a passageway in the material being mined to permit the machine to advance, means for adjusting said head vertically relative to said mobile base, a conveyor carried by said head and positioned on said head immediately to the rear of said cutting means for receiving the disintegrated material, and said conveyor extending transversely of said mobile base to convey such material to one side of said head in advance of said mobile base.

3. A mineral mining and loading machine comprising, a mobile base, a mining head pivotally secured to said mobile base adjacent one end thereof to be vertically movable with respect thereto, said mining head extending outwardly beyond said one end of said mobile base, said head having a cutting or disintegrating means for removing material from the mineral face to provide a passageway in the material being mined to permit the machine to advance, means for adjusting said head vertically relative to said mobile base, said mining head having a chamber immediately to the rear of said cutting means for receiving the dislodged and disintegrated material from said cutting means, and a conveyor extending transversely of said mobile base and along the bottom of said chamber for conveying the material from the chamber transversely of the head to one side thereof in advance of said mobile base.

4. A mineral mining and loading machine comprising, a mobile base, a mining head pivotally secured to said mobile base adjacent one end thereof to be vertically movable with respect thereto, said mining head extending outwardly beyond said one end of said mobile base, said head having a cutting or disintegrating means for removing material from the mineral face to provide a passageway in the material being mined to permit the machine to advance, means for adjusting said head vertically relative to said mobile base, said mining head having a chamber immediately to the rear of said cutting means for receiving the dislodged and disintegrated material from said cutting means, and a conveyor extending transversely of said mobile base at the bottom of said head beneath the chamber to provide the bottom of the chamber and operative to convey the material collected in 75

the chamber transversely of the head to one side thereof in advance of said mobile base.

5. A mineral mining and loading machine comprising, a mobile base, mining heads pivotally secured to the ends of said base respectively and vertically movable with respect thereto, each of said heads extending outwardly of the ends of said base respectively and carrying a cutting or disintegrating means for removing material from a mineral face in the direction the machine at the moment is advancing to provide a passageway in the material being mined to permit the machine to advance, means for adjusting said heads vertically relative to said mobile base respectively, and a transversely extending conveyor carried by each of the heads respectively and operative 10 to convey the cut or disintegrated material laterally to one side of the advancing end of said mobile base.

6. In a longwall mining machine, a mobile base movable along a path parallel with the face of a mine vein, a head mechanism pivotally mounted on said base to tilt relative thereto about a transverse axis located near the forward portion of said base, said head mechanism extending forwardly in advance of said base and having mineral disintegrating means for disintegrating the mineral to form the roof, sidewall and floor of a passageway inside of and parallel with the vein face, means for tilt 20 ing said head mechanism relative to said base and for holding the same in different tilted positions, said head mechanism having a chamber disposed rearwardly of said disintegrating means transversely between the sides of the latter for receiving the dislodged and disintegrated mineral, and a transverse conveyor extending along the bottom of said chamber for receiving the disintegrated mineral and for conveying the same transversely of the head mechanism to discharge at one side of the machine 30 path.

7. A mineral mining and loading machine comprising a mobile base, a mining head pivotally secured to said mobile base adjacent one end thereof to be vertically movable with respect thereto, said mining head extending outwardly beyond said one end of said mobile base, said head having a cutting or disintegrating means for removing material from the mineral face to provide a passageway in the material being mined to permit the machine to advance, means for adjusting said head vertically relative to said mobile base, a conveyor carried by said head in advance of said base and having its receiving portion disposed immediately to the rear of said cutting or disintegrating means for receiving the disintegrated material, and said conveyor having its discharge portion at one side of said head to effect discharge of the material conveyed by said conveyor at one side of said machine in advance of said base and out of the path of the latter.

8. A mineral mining and loading machine comprising a mobile base, a mining head pivotally secured to said mobile base adjacent one end thereof to be vertically movable with respect thereto, said mining head extending outwardly beyond said one end of said mobile base, said head having a cutting or disintegrating means for removing material from the mineral face to provide a passageway in the material being mined to permit the machine to advance, means for adjusting said head vertically relative to said mobile base, a conveyor carried by said head in advance of said base and having its receiving portion disposed in a relatively low position below the top of said base immediately to the rear of said cutting or disintegrating means for receiving the disintegrated material, and said conveyor having its discharge portion at one side of said head to effect discharge of the material conveyed by said conveyor at one side of said machine in advance of said base and out of the path of the latter.
